UNITED STATES PATENT OFFICE.

JAMES J. BILLINGSLEY, OF MINDEN, LOUISIANA.

RAILWAY-FROG.

SPECIFICATION forming part of Letters Patent No. 349,978, dated September 28, 1886.

Application filed January 4, 1886. Serial No. 187,613. (No model.)

To all whom it may concern:

Be it known that I, JAMES J. BILLINGSLEY, a citizen of the United States, residing at Minden, in the parish of Webster and State of Louisiana, have invented certain new and useful Improvements in Railway-Frogs, of which the following is a specification, reference being had therein to the accompanying drawings.

My invention relates to railway-frogs; and it consists in the parts which will be herein-after described, and pointed out in the claim.

In another application for Letters Patent of the United States I describe, illustrate, and claim a double flanged locomotive and car wheel.

It is the object of this invention to provide a frog that will be suited to the wheel therein shown.

In the accompanying drawings, forming part of this application, Figure 1 represents a plan view of a portion of the main track and switch with my frog at the intersection of the rails. Fig. 2 is a perspective view of the central block forming the main feature of my invention, and Fig. 3 is a plan view of the same.

Like letters indicate like parts in the several views.

A A' represent the main-line rails, and B the cross-ties on which they rest. The inner main rail, A', lying nearest the side-track, is cut away between the points where one of the side-track rails C intersects it. Said side-track rail C is also cut away at the point where it intersects the main-track rail A'. The cut-away ends of the intersecting rails are beveled from side to side. The degree to which the ends are beveled depends on the angle of inclination of the side track at the point of intersection with the main line.

C indicates the outside side-track rail.

D represents the block proper, which is interposed between the ends of the intersecting rails A' and C. The sides of this block are vertical, so as to admit of the free passage of either a single or a double flanged wheel. 45 Wheels of either construction may pass freely along the main line, or may be admitted to the side track, as may be desired. The block D is provided with bottom side flanges, D', having openings D² therein for the reception 50 of spikes for securing the same to the cross-ties or underlying plate or block, as may be desired. These flanges, if desired, may extend from all sides of the block.

E represents a plate resting upon the cross-ties under the frog. The plate is secured to the ties, and the frog is secured to the plate.

F F represent guard-rails.

My frog may be also employed at a point where one railroad crosses another at right angles. In that case the ends of the rails at the point of intersection would be cut off square, and the intervening block would also have a square face.

Having thus described my invention, I claim as new and desire to secure by Letters Patent of the United States—

A railway-frog consisting of a quadrilateral block with vertical sides, provided with bottom side flanges, D', having openings D² therein for the reception of spikes for securing the same to the cross ties or underlying plate or block, substantially as specified.

In testimony whereof I affix my signature in presence of two witnesses.

JAMES J. BILLINGSLEY.
